UNITED STATES PATENT OFFICE.

LEWIS S. HARALDSON, OF ROWENA, SOUTH DAKOTA.

BOX-CAR DOOR.

Application filed February 18, 1925. Serial No. 10,114.

To all whom it may concern:

Be it known that I, LEWIS S. HARALDSON, a citizen of the United States, residing at Rowena, in the county of Minnehaha and 5 State of South Dakota, have invented certain new and useful Improvements in Box-Car Doors, of which the following is a specification.

This invention relates to improvements in 10 slideable doors particularly adapted for use upon railroad box cars but also adapted for motor trucks and similar vehicles.

An important object of the invention is 15 to provide a door of the above mentioned character which may be partially opened for the removal of the contents of the box car or vehicle body.

A further object of the invention is to 20 provide a door of the above mentioned type adapted to permit progressive filling of the box car with matter such as grain or the like.

A still further object of the invention is 25 the provision of a door of this character which is easily operable, durable, yet comparatively simple in construction.

Other objects and advantages of this invention will be apparent during the course 30 of the following description.

In the accompanying drawings forming a 35 part of this specification and in which like numerals are employed to designate like parts throughout the same:

Figure 1 is a transverse sectional view 40 through a car body showing my improved device mounted in connection therewith,

Figure 2 is a vertical sectional view taken from the interior partially showing the door construction,

Figure 3 is a similar view taken from the 45 outside of the car body,

Figure 4 is a perspective view illustrating the construction of the guide members,

Figure 5 is an enlarged horizontal section 50 view showing the detailed construction of the door guide means,

Figure 6 is a vertical sectional view showing the upper door section in open position,

Figure 7 is a front elevation of a removable plate,

Figure 8 is a vertical sectional view showing the manner of mounting the same,

Figure 9 is a front elevational view illustrating the construction of elevating bars 55 for the door, and

Figure 10 is a detailed view illustrating

the construction of a section retaining plate.

In the drawings, wherein for the purpose of illustration is shown the preferred embodiment of my invention, the numeral 12 generally indicates the longitudinal beams of the box car body, and 13 the transverse brace beams. The numeral 14 designates the floor boards built upon the brace beams and 15 the roof construction. Secured to upper 60 longitudinal beams 12 adjacent the roof are a pair of oppositely disposed header beams 16 adapted to form supports for my improved door. It is customary that box cars of this type be provided with door frames, 65 usually two directly opposed vertical door posts 17 connecting with the upper and lower longitudinal body beams to complete the structure.

The foregoing description has dealt 70 generally with the usual box car construction and forms no part of my invention being shown merely for the purpose of clearly describing the cooperating thereof with the elements comprising my invention. 75

Referring now more particularly to my improved door the numeral 18 designates a supporting beam secured to the central portion of the roof 15 having a pair of guide supporting brackets 19 fastened near the 80 extremities thereof. The lower extremities of the brackets 19 are provided with horizontal brace plates bolted or otherwise secured to a horizontal guide rail 20. This rail is substantially in the shape of a 85 widely spread V conforming to the general contour of the roof, the extremities being bent to extend vertically downward for a short distance. The guide rail 20 is constructed of a pair of angles, as clearly shown 90 in Figures 2 and 4, the longer back legs thereof over-lapping and connected by bolts and the extreme edges of the shorter legs being provided with guide flanges 21. For the purpose of permitting convenient construction of the device I consider it advisable to form the transverse guide rail 20 of two sections connected by the brace plate 95 formed on the bracket 19 secured to the central portion of the car roof.

A pair of vertical side rails 22 connect 100 with the lower extremities of the guide rail 20 forming a substantially U-shaped rail extending about the sides and roof of the car. The side rails 22 are somewhat similar 105 in construction to the transverse guide rail 20 differing only in the increased length of 110

the projecting legs of the angles, the purpose of which will be hereinafter more fully described. These rails are secured to the door posts 17 by a plurality of suitably spaced bolts 23 extending through the extension legs of the rails and the door posts. In order to securely fasten the lower extremities of the side rails 22 I provide angular base plates 24 bolted to the interior legs 10 of the rails and to the car floor.

The upper extremity of my door structure comprises a comparatively wide swinging section 25 preferably constructed of wood and provided about the edges with protecting strips of metal or any desirable material. The upper edge of this swinging section is provided with a pair of hinges 26 secured to the section and to a vertically movable strip 27 mounted on the inner edge 15 of the header beams 16. The extremities of the movable strip 27 are provided with longitudinally extending ears 28 apertured to engage vertical guide bolts 29. The intermediate portions of the movable strips are provided with vertical slots 30 engageable with 20 studs 31 having enlarged heads formed on the outer extremities thereof to prevent displacement of the strip. Coiled compression springs 32 are positioned between the upper 25 head of the guide bolts 29 and the ears 28 normally tending to force the strip 27 downwardly. The lower portion of the car door structure is composed of a plurality of comparatively narrow sections 33 rectangular in 30 cross-section and preferably constructed of wood. These sections are also provided with metallic strips or strips of suitable material about the edges designed to protect the same. The extremities of the sections 33 carry 35 longitudinal extending shafts 34 securely fastened in the sections and adapted to rotatably support on the ends thereof roller bearings 35 secured against displacement by countersunk heads formed on the extremities 40 of the shaft or in any suitable manner. The roller bearings are spaced from the extremities of the sections 33 by a bearing sleeve 36 positioned between the section and roller bearings.

45 It is thus noted that the narrow sections 33 are readily movable upon the guide rails in a vertical plane, lateral movement being prevented by the guide flanges formed on the rails. When the narrow guide sections 50 33 are positioned in the upper transverse guide rail and depending sections adjacent thereto the roller bearings are positioned between the outer guide flanges and the vertical legs of the rail. The bearing sleeve 36 travels between the guide flanges, the body 55 of the sections 33 in this instance being all together outside the rail. When these sections engage the lower portions of the vertical side rails the extreme ends of the sections extend substantially within the rails,

due to the increased length of the side legs of the rails. As clearly shown in Figure 5 the legs on the outer side of the rail are substantially longer than those on the inner side. This arrangement is considered desirable so that rain, dust or other undesirable matter may be excluded from within the car. In order that the movable sections 33 may be readily raised or lowered upon the guide rails I provide handles 37 on the outer 75 sides thereof adjacent the extremities, these handles being preferably constructed of U-shaped metallic rods having horizontal inwardly projecting lugs rotatably engaging suitable eye bolts. When it is desirable to remove one or more of the sections from the rails the roller shaft and bearings are removed from the door sections through suitable openings formed through the over-lapping legs of the rails, one of these openings 80 being shown at 38. These openings are normally enclosed by a cover plate 39 secured to the rails by bolts 40 or in any suitable manner.

The upper swinging guide section 25 is 90 also provided with a pair of handles 37 near the lower edge thereof, the upper portion carrying a pair of hinge stop members 39'. One section of these hinge members is bolted to the door while the other section swings 95 about the hinge pin, this latter section being gravity actuated. As clearly shown in the closed door section of Figure 1 the movable hinge member formed on the lower portion of the hinge extends vertically downward 100 parallel with the upper door section. When this section is swung upwardly in the open position as clearly shown in Figure 6, the movable portion of the hinge swings downwardly to a position at approximately right 105 angles to the door section and is restricted from further movement by a suitable projection. The purpose of this hinge member is well shown in the left hand portion of Figure 1, wherein the movable portion of the hinge 39 is shown engaging one of the 110 movable door sections preventing downward movement thereof. The lower edge of the door section 25 carries a retaining plate 40 bolted or otherwise secured thereto and provided at the projecting end with a rectangular opening 41. In the open position of the door the projecting edge of the retaining plate 40 suitably engages a hook 42 secured to the box car roof retaining the 115 swinging structure in position. In the closed position of the door the projecting extremity of the retaining plate overlaps the upper portion of the top movable section 33 preventing movement of the swinging section. 120 When it is desirable to open the door the upper swinging section is elevated, disengaging the retaining plate from the movable sections and permitting the same to be 125 readily swung to the open position.

In certain instances it is desirable that the lower portion of the door only be opened and the grain or other matter stored in the car removed by shoveling in any desirable manner. This may be accomplished by elevating the upper swinging door section and swinging the same inwardly sufficiently to disengage the upper edge of top movable section whereby the movable sections may be elevated by means of jack hooks engageable with suitable elevating bars 42 formed in the central portion of the lower movable section.

In operating, the doors may be readily manipulated to the opened or closed positions as clearly shown in Figure 1. As heretofore described, the upper swinging section is first elevated in alignment with the movable sections then swung upwardly until the retaining plate on the lower edge thereof engages the hooks 42 retaining this section in the upward position against the roof of the car. The bottom sections are then raised and rolled around in the guide rails this movement being readily accomplished by means of the handles 37 secured to the sections. When the narrow sections 33 have been positioned in the upper horizontal rail they will be retained thereon by means of the stop hinge 39 which will engage the lowermost section and prevent the sections sliding downwardly. To close the doors the movable portion of the stop hinge 39 is swung upwardly whereby the narrow door sections will readily descend into their closed positions by gravitation, the upper swinging section being released from the hook and swung to the closed position shown in Figure 1. It is obvious that this door section possesses many advantages over the many patented devices intended for this purpose as most of these have been found generally impractical. It is contended that this device is highly practical and will meet the demand for a durable yet inexpensive door of this character. The structure may be readily applied to most box cars now in use without great expense or material alteration thereof and it is further contended eventually result in substantial saving due to the ease of operation and efficiency as closure means.

It is to be understood that the form of my invention herewith shown and described is to be taken as the preferred example of the same, and that various changes as to the shape, size and arrangement of parts may be resorted to without departing from the spirit of the invention, or the scope of the subjoined claims.

Having thus described my invention, I claim:

1. A device of the character described including a substantially U-shaped guide rail, a plurality of movable sections adapted to

engage the said guide rails, a swinging section mounted above the uppermost of the movable sections, and means for readily opening or closing the said sections.

2. In combination with a vehicle body comprising a floor, a roof, a door frame, and a header beam adjacent the roof, of a pair of guide rails extending adjacent the side and roof of the body, a plurality of movable sections, means formed on the extremities of the sections for engaging the guide rails, a swinging section hingedly mounted on the upper portion of the body, and means for retaining the sections in open position.

3. In combination with a vehicle body comprising a floor, a roof, door frames including door posts, and a pair of longitudinal header beams secured above the door frames, a pair of oppositely disposed guide rails extending adjacent the sides of the door frame and roof, a plurality of movable door sections, rollers mounted on the extremities of the movable sections adapted to engage the guide rails, a pair of swinging sections hingedly connected to the said longitudinal header beams, means whereby the swinging sections will retain the movable sections in open position, and means formed on the said swinging and movable sections for actuating the same.

4. In combination with a box car and door frames formed in the sides of the box car, of a door including a pair of opposite disposed guide rails built of angle members having guide flanges formed on the outer extremities, the said guide rails extending on the sides adjacent the door frame and roof of the box car, a pair of comparatively wide swinging sections hinged to a pair of header beams mounted adjacent the roof of the car, a plurality of comparatively narrow sections movable upon the said guide rails, roller bearings mounted on the extremities of the movable sections adapted to engage the guide rails, handle members secured to the swinging section and movable section for readily operating the same, openings formed in the guide rails for removing the guide sections, means for retaining the swinging sections in an open position, and a stop hinge formed on the swinging section adapted to engage and retain the movable sections upon the upper transverse rail.

5. In combination with a vehicle body having oppositely disposed door frames formed in the sides thereof, of doors adapted to close the vehicle body including a pair of substantially U-shaped guide rails secured to the side and roof of the body, a pair of comparatively wide swinging sections movably mounted on a suitable beam, a plurality of narrow sections movable on the said guide rails, means secured to the extremities of the said narrow sections adapted to engage the guide rails, means formed

- on the sections for readily operating the same, movable stop members secured to the upper swinging section adapted to retain the movable sections in open position, and
- 5 means for readily releasing the said movable sections.
6. In combination with a vehicle body having door frames formed in the sides thereof, of sectional doors including guide
- 10 rails formed adjacent and secured to the side and roof of the vehicle body, guide flanges formed on the extension legs thereof, a comparatively wide swinging door section hingedly mounted upon a supporting
- strip, the said strip being movably carried 15 by a suitable longitudinal beam, a plurality of sections forming the lower portion of the doors and movable in alignment with the guide rails, rotatable extensions secured to the movable sections adapted to engage 20 the guide rails, means formed on the swinging and movable door sections for operating the same, and means for retaining the said sections in open position.
- 25 In testimony whereof I affix my signature.

LEWIS S. HARALDSON.
